Patented Apr. 15, 1919.

FIG. 2.

John C. Schrade

Inventor

By *Geo. P. Kimmel.*

Attorney

UNITED STATES PATENT OFFICE.

JOHN C. SCHRADE, OF ROCKAWAY BEACH, NEW YORK.

PIPE-SEAL.

1,301,010.

Specification of Letters Patent. Patented Apr. 15, 1919.

Application filed March 6, 1917. Serial No. 152,732.

To all whom it may concern:

Be it known that I, JOHN C. SCHRADE, a citizen of the United States, and resident of Rockaway Beach, in the county of Queens 5 and State of New York, have invented certain new and useful Improvements in Pipe-Seals, of which the following is a specification.

The present invention relates to the class 10 of water distribution and has a particular reference to new and useful improvements in seals for vitrified and cement pipe sewers.

The primary object of my invention is to provide a closure means for the mouth or 15 bell of the vitrified or cement pipe which may be constructed at a small cost, that is adapted to be detached without injury to the pipe, and yet having the desired characteristics to provide a permanent pipe seal 20 if such be desired.

A still further object of my invention is to provide a pipe closure of the class described which is adapted to be used with Y or T branches as well as with the main pipe 25 line.

Other improvements and novel details in the construction and arrangement of the various parts of the apparatus will be brought out more in detail in the description 30 to follow, which, for a clear understanding of the invention, should be considered in connection with the accompanying drawing, forming a part hereof, and wherein is disclosed, for the purpose of illustration, convenient and satisfactory embodiments of the 35 invention. It is to be noted, in this connection, that minor changes in the construction and details of the invention may be made without departing from the spirit or scope 40 of the invention.

In the drawing:

Figure 1 is a perspective view of my invention, and

Fig. 2 is a longitudinal sectional view 45 thereof.

Corresponding and like parts are referred to in the following description and indicated in all of the views of the drawing by the same reference characters.

50 My improved pipe seal or closure comprises a cap member, designated C in its entirety, having an end portion 11 provided with a concentrically arranged inwardly extending enlargement 12 adapted to be seated

at the jointure of the end of the pipe 13 55 with the mouth or bell portion 14 thereof. A laterally extending flange 15 is provided on the edge of the end portion of the cap member and is adapted to embrace the bell or flared mouth portion and also a part of 60 the pipe. The flange 15 is provided with grooves 16 for a purpose which will be hereinafter described. Semi-circular indentures 17 are provided on the opposite sides of the cap member to permit that portion thereof 65 within the semi-circular indenture to be removed and thus permit the use of my improved cap with a Y or T branch.

To provide means for facilitating the breaking or removal of the end portion 11, an 70 annular groove 20 is formed therein. Thus, by tapping the same with a hammer or other suitable implement, the end may be readily broken from the cap.

After the cap member has been inserted 75 over the head of the pipe to be inclosed and the enlargement 12 is resting on the end of the pipe adjacent the jointure of the bell or mouthpiece thereof a piece of oakum or jute 18 is inserted between the bell portion 14 80 and the side of the cap after which concrete 19 is inserted between the exposed end of the cap and the pipe. After the concrete settles and becomes hardened the same will provide the desired airtight and waterproof closure. 85 When it is desired to remove the cap portion after the same has accomplished the desired purpose, by a strike of the hammer the cap member will break along the groove portion 16 and thus permit the removal thereof. It 90 is of course to be understood that my cap member is made of concrete or earthenware, having the grooves and indentures above-mentioned marked therein before the same has become burned, i. e., before it has been 95 placed in the roasting furnace.

Having thus fully described my invention, what I claim as new and desire to secure by Letters Patent, is:—

1. In a device of the class described, the 100 combination with a pipe and a bell portion provided on one end thereof, of a cap member adapted to embrace the said bell portion and a portion of the pipe and having a plurality of longitudinally extending grooves 105 therein.

2. In a pipe seal, a cap member having a plurality of semi-circular indentures therein

providing means for facilitating the removal of the semi-circular portion within the semi-circular indentures to adapt the cap member for use with various designed pipes.

5. 3. In a pipe seal, a cap member having a plurality of longitudinal and semi-circular grooves formed in the sides thereof and an

annular groove formed in the end thereof, said longitudinal groove terminating at points adjacent the annular groove, as and 10 for the purpose set forth.

In testimony whereof, I affix my signature hereto.

JOHN C. SCHRADE.
